CLAIM

The ornamental design for a folding chair with detachable container in combination as shown and described.

DESCRIPTION

FIG. 1 is a front-left perspective view of folding chair with detachable container in combination showing the new design;

FIG. 2 is a front-right perspective view thereof;

FIG. 3 is a front-top perspective view thereof; and,

FIG. 4 is a rear-left perspective view thereof.

The broken lines depict portions of the folding chair with detachable container in combination that form no part of the claimed design.
